iden, Conn., a corporation of Delaware

Application August 11, 1943, Serial No. 498,138

7 Claims. (Cl. 177—311)

1

The present invention relates to safety signal apparatus for use on aircraft, and particularly to signal apparatus for indicating to the pilot of an aircraft that the mixture of fuel and air being supplied to an engine of the aircraft is of improper proportions.

On most modern aircraft, a control lever is provided by which the pilot may determine whether the carburetor is to supply the engine with a rich fuel and air mixture, or a lean mixture. It is desirable for reasons of economy to operate with a lean mixture under most flight conditions. However, if the engine is operated with a lean mixture under conditions of high power requirements, it may overheat. Furthermore, it may not produce the required power. Therefore a control lever is provided by which the pilot may cause the engine to be supplied with a rich mixture under such conditions as take off or climbing, while he may select a lean mixture for normal or cruising flight.

It has been found that pilots sometimes forget to operate this lever at the proper time. Since the lever is usually moved to the rich position for take off, it may be left at that position for a considerable time after the plane has reached its cruising altitude. This results in excessive fuel consumption, and may result in the plane's fuel supply running low before its destination is reached, with consequent necessity of a forced landing. Where a land plane is operated over water, for example, the plane and all its occupants may be lost merely because the pilot forgot to restore the mixture control lever to the lean position for cruising operation.

On the other hand, if the pilot allows the lever to remain in the lean position when it should be moved to the rich position, the engine may not produce sufficient power to take off, climb, or perform some other desired maneuver.

It is well known that an engine runs cooler with a rich fuel and air mixture than with a lean mixture. At high altitudes, the normal cooling apparatus of an engine does not function as well as at lower altitudes because of the lower density and lower specific thermal capacity of the air. Consequently, aircraft engines are usually operated with a rich mixture at high altitudes so as to provide a cooler operating temperature for the engine.

It is therefore an object of the present invention to provide a signal system for use with an aircraft carburetor having a mixture control lever, which system indicates to the pilot whether

2

or not the mixture control lever is in the proper position for the existing flight conditions.

Another object of the present invention is to provide a signal system responsive to the attitude of an aircraft and to the position of a carburetor mixture control lever, for indicating to the pilot when the mixture control lever is in the wrong position for the flight of the aircraft in its existing attitude.

10 Another object is to provide a signal system responsive to the rate of climb of an aircraft and to the position of a carburetor mixture control lever, for indicating to the pilot when the mixture control lever is in the wrong position for the flight of the aircraft at its existing rate of climb.

Another object of the present invention is to provide a signal system responsive to the position of an aircraft carburetor mixture control lever and to the altitude of the aircraft for indicating 20 to the pilot when the mixture control lever is in an improper position for operation of the aircraft at the particular altitude at which it is flying. A further object is to provide, in a carburetor equipped with altitude compensating means, an 25 arrangement for utilizing that altitude compensating means in a signal system of the type described.

Other objects and advantages of the present invention will become apparent from a consideration 30 of the appended specification, claims, and drawings in which

Figure 1 represents, somewhat diagrammatically, an aircraft carburetor provided with a signal system built in accordance with the principles 35 of my invention.

Figure 2 illustrates an improved switching device which may be used in the system of Figure 1, and

Figures 3 and 4 are electrical wiring diagrams 40 showing the circuits of Figures 1 and 2, respectively.

In Figure 1, there is shown a carburetor body portion 10 thru which air flows from an inlet 11 thru a passage 12 to an outlet 13. In flowing 45 thru the passage 12, the air passes a Venturi restriction 14, a throttle 15, and a fuel discharge nozzle 16.

A second air passage connects the inlet 11 and the throat of the Venturi restriction 14. This 50 second air passage may be traced from the inlet 11 thru a plurality of impact tubes 17, whose open ends project into the inlet 11, a vent ring passage 18 interconnecting the impact tubes 17, a conduit 20, an expandible chamber 21 in a fuel regulator unit 22, a restriction 23, an expandible chamber

24 in the regulator unit 22, a conduit 25, an expansible chamber 26 in an altitude responsive switch unit generally indicated at 27, a conduit 28, a chamber 30, and a conduit 31 to the throat of Venturi restriction 14.

A bellows 32 is mounted in the chamber 30, and operates a valve 33 which controls the flow of air from the passage 29 into the chamber 30. The bellows 32 is preferably filled with nitrogen or other inert temperature responsive fluid, so that the position of valve 33 is determined by the temperature and pressure of the air in the chamber 30, and hence by the density of that air.

The valve 33 restricts the flow of air thru the second passage just described in such a manner that the pressure differential between chambers 21 and 24 is an accurate measure of the mass of air flowing thru the passage 12. Errors due to changes in the density of the air with altitude and temperature, and also those errors due to the inherent limitations of a metering restriction of the Venturi type, are substantially eliminated by the operation of valve 33. This type of metering error compensation is more completely described and claimed in my co-pending application Serial No. 490,281, filed June 10, 1943, now Patent No. 2,393,144, issued January 15, 1946.

The fuel passing thru the carburetor comes from a fuel pump or other source of fuel under pressure (not shown). From this source, the fuel passes thru a conduit 34, a fuel regulator unit 22, a conduit 35, a mixture control valve 36, a jet system 37, a conduit 38, a pressure regulator valve 40, and a conduit 41 to the discharge nozzle 16.

The fuel regulator unit 22 comprises a housing 42, which is divided by three flexible diaphragms 43, 44 and 45 into four expansible chambers 46, 21, 24 and 47. The diaphragms 43, 44 and 45 are interconnected by a valve stem 48, which carries a balanced valve member 50 at its lower end. A compression spring 51 biases the stem 48 for movement of the valve 50 toward open position.

The pressure in chamber 47 is substantially equal to the pressure existing on the upstream side of the jet system 37. Chamber 46 is connected thru a conduit 52 to an expansible chamber 53 in the pressure regulator 40. Therefore the pressure in chamber 46 is substantially equal to that existing on the downstream side of the jet system 37. The differential between these pressures is a measure of the quantity of fuel flowing thru the carburetor. This pressure differential is transmitted to the chambers 47 and 46, as described above, where it acts on the valve 50 in a closing direction. As previously pointed out, the pressure differential between chambers 21 and 24 is a measure of the mass of air flowing thru the passage 12, and acts on the valve 50 in an opening direction. Therefore, the valve 50 is operated to proportion the quantity of fuel flowing thru the carburetor in accordance with the mass of air passing thru the passage 12.

The mixture control valve 36 includes a casing 54 forming a generally cylindrical chamber having an inlet port 55 and outlet ports 56 and 57 entering one end of the chamber. A disc valve 58 is fixed in a shaft 60 which passes axially thru the chamber. The inlet port 55 is connected to the conduit 35. The outlet port 56 is connected by a conduit 61 to the jet system 37, and the outlet port 57 is connected by a conduit 62 to the jet system 37. The shaft 60 may be rotated by a manual control (not shown) so that the disc valve 58 is moved to cover the outlet port 56, or both the outlet ports 56 and 57. When the mixture control

is in the position shown in the drawing, both outlet ports are open, and the mixture control is said to be in its rich position. When the mixture control is in the dotted line position shown in the drawing, wherein the port 56 is closed but the port 57 is open, the mixture control is said to be in its lean position. When both the ports 56 and 57 are cut off by the disc valve 58, the mixture control is in its cut-off position.

Fuel flowing thru the conduit 62 passes thru a fixed restriction or jet 63 in the jet system 37 to the conduit 38. Fuel flowing thru the conduit 61 passes thru a fixed restriction 64 and a second fixed restriction 65 to the conduit 38. Fuel entering the jet system 37 thru the conduit 62 may also flow thru a restricted passage 66 to the upstream side of the restriction 65. The passage 66 is normally closed by a spring loaded valve 67, which is adapted to open when the pressure differential across it exceeds a predetermined value. By the operation of the valve 67, the fuel and air mixture supplied to the engine is automatically enriched when the power requirements of the engine are high. An idle valve 69, which may be operated thru linkage not shown, in accordance with changes in throttle position, is provided to control the fuel flow when the engine is idling. Under such conditions, the air flow is so small that the controlling effect of the pressure differential between chambers 21 and 24 is overcome by spring 51, which moves valve 50 toward open position. In effect, at low air flows, control of the fuel flow is transferred from the air flow responsive regulator unit 22 to the throttle operated idle valve 69. This is done because at small air flows, the regulating effect of the air flow responsive regulator unit is unstable.

The pressure regulator unit 40 includes a casing 70 divided by a diaphragm 71 into a pair of expansible chambers 72 and 53. The diaphragm 71 carries a valve 73 which controls the flow of fuel between the chamber 53 and the conduit 41. A conduit 74 connects the chamber 72 with the conduit 20, and thru conduit 20, vent ring 18 and the impact tubes 17 to the air inlet 11. The conduit 74 is provided as a vent for the chamber 72 to permit easy movement of the diaphragm 71. A spring 75 biases the valve 73 for movement toward open position. The pressure in chamber 72 is low compared to the pressure in chamber 53 and the force of the spring 75, so that the pressure in chamber 72 has substantially no controlling effect on the position of valve 73. The valve 73 therefore functions primarily as a pressure regulator to maintain a substantially constant pressure on the discharge side of the jet system 37.

From the foregoing, it will be seen that when the mixture control is in the rich position shown in full lines in the drawings, fuel is supplied to both restrictions 63 and 64. On the other hand, when the mixture control is in the lean position shown in dotted lines in the drawings, fuel is supplied only thru the restriction 63. In either position of the mixture control, the valve 67 may open when the power requirements of the engine are high to further enrich the fuel and air mixture.

Signal system

A switch arm 80 is attached to the shaft 60 and insulatingly carries at its end a movable contact 79 which cooperates with a pair of stationary contacts 81 and 82. When the mixture control is in the rich position, the contact 79 engages contact 82. When the mixture control is in the lean position the contact 79 engages contact 81.

5

A gravity responsive switch mechanism is shown at 83. In this mechanism, a pendulum 84 is provided with a pair of movable contacts 85 and 86 which cooperate respectively with stationary contacts 87 and 88. The pendulum 84 is so arranged that contact 85 engages contact 87 whenever the aircraft is in level flight or diving, while the contact 86 engages contact 88 whenever the aircraft is climbing. While a gravity responsive switch is illustrated, it will be readily understood that this may be replaced by a gyroscope or other device which operates a switch in accordance with the attitude of the aircraft.

The altitude responsive switch 27 includes a casing 90 divided by a flexible diaphragm 91 into a pair of expansible chambers 26 and 92. The central portion of diaphragm 91 insulatingly carries bridging contacts 93 and 94 on its opposite sides. The bridging contact 93 is adapted to engage and electrically connect a pair of stationary contacts 95 and 96, and the bridging contact 94 is adapted to electrically connect a pair of stationary contacts 97 and 98. A compression spring 100 biases the diaphragm 91 for movement to the left.

The chamber 92 is connected thru a conduit 101 to the chamber 30. As previously described, the chamber 26 is connected thru conduit 28 and valve 33 to chamber 30. Therefore the pressure differential between the chambers 26 and 92 is the same as that existing across the valve 33. Since the valve 33 is operated by the bellows 32 toward closed position with increasing altitude, it may be seen that the pressure differential between chambers 26 and 92 is in a direction to move diaphragm 91 to the right and that this differential increases with increasing altitude. The effect of the altitude responsive switch unit 27 is to move the bridging contact 93 into engagement with contacts 95 and 96 whenever the aircraft is operated below a first predetermined altitude, and to move the bridging contact 94 into engagement with contacts 97 and 98 whenever the aircraft is operating above a second predetermined altitude.

The switch unit 27 also responds to air flow, i.e., to the quantity of air flowing thru the passage 12. When the air flow increases, the pressure differential across valve 33 increases, for a given setting of that valve. Therefore it may be seen that, for any given altitude, the switch unit 27 closes its contacts at some particular value of air flow, depending on the characteristics of spring 100. Furthermore, the particular air flow at which the switch unit 27 closes its contacts depends upon and varies with altitude. Altitude and air flow act cumulatively in the switch unit 27. That is, increase in altitude, which signifies the need for a richer fuel and air mixture, acts in the same direction as an increase in air flow, which likewise signifies the need for a richer fuel and air mixture.

The altitude responsive switch unit 27 and the gravity responsive switch unit 83, together with the switch contact 79 associated with the mixture control 36, control the energization of a pair of signals 102 and 103. As indicated schematically in the drawing, the signals 102 and 103 may be electrically illuminated signals provided with the legends "Go to rich" and "Go to lean" respectively.

When the various switch units are in the positions shown in the drawings, the mixture control is in the rich position and the aircraft is operating in level flight, and above the altitude at which bridging contact 93 engages the stationary contacts 95 and 96. At this particular inter-

6

mediate altitude, the power requirements of the engine are such that the engine may operate with either a rich or lean mixture. If the aircraft now decreases its altitude, contact 93 is moved into engagement with stationary contacts 95 and 96, thereby completing an energizing circuit for signal 103. This circuit may be traced from the upper terminal of a battery 104 thru a conductor 105, pendulum 84, contacts 85 and 87, conductor 106, contacts 96, 93 and 95, a conductor 107, signal 103, contact 82, contact 79 and a conductor 108 to the lower terminal of battery 104. Energization of signal 103 informs the pilot that the mixture control should be moved to its lean position. As soon as it is so moved, the energizing circuit for signal 103 is opened by movement of contact 79 away from contact 82.

If, when the mixture control is in the lean position, the aircraft starts to climb, the pendulum 84 moves contact 86 into engagement with contact 88. This completes an energizing circuit for signal 102, which may be traced from the upper terminal of battery 104 thru conductor 105, pendulum 84, contacts 86 and 88, conductors 110 and 111, signal 102, contact 81, switch contact 79 and conductor 108 to the lower terminal of battery 104.

If the altitude of the aircraft is above a predetermined value, bridging contact 94 engages stationary contacts 97 and 98, thereby completing an energizing circuit for signal 102 which may be traced from the upper terminal of battery 104 thru conductors 105 and 112, contacts 97, 94 and 88, conductors 113, and 111, signal 102, contact 81, switch contact 79, and conductor 108 to the lower terminal of battery 104.

From the foregoing, it should be apparent that whenever either of the signals 102 and 103 is energized, it remains energized until the mixture control is moved to the position whose necessity is indicated by the signal, and that upon such movement of the mixture control the switch arm 30 breaks the circuit to the signal so that it is no longer energized.

Figure 2

There is shown in Figure 2 a switch mechanism whereby a signal system of the type shown in Figure 1 may be operated in accordance with the rate of climb of an aircraft and in accordance with the quantity of air entering the carburetor. The switch mechanism of Figure 2 may be substituted for the switch 83 of Figure 1. It is desirable to have the carburetor mixture control in its rich position when the aircraft is climbing in order that the engine may operate under the best conditions for producing maximum power without overheating. It has been found that an engine runs cooler for a given power output when it is supplied with a rich mixture than when it is supplied with a lean mixture. Also, the quantity of air entering the carburetor serves as an indication of the amount of power required at any given time. When the air flow is high, the amount of power developed is high. Under such conditions, the engine should be operated with a rich mixture to prevent overheating of the engine.

Referring now to Figure 2, there is shown a generally cylindrical casing 125 suitably attached to a base 126. Inside the casing there is mounted on the base 126 a bellows 127. A spring 128 is compressed between the bellows 127 and the base 126. A pair of guide members 130 and 131

project from the base 126 and maintain the spring 128 in proper alignment. The exterior of bellows 127 is exposed to atmospheric pressure thru suitable openings 129 in the casing 125. A passage 132 extends horizontally from the space adjacent the exterior of bellows 127 to a vertical passage 133 which extends upwardly through the base 126 and is concentric with bellows 127. An elongated nozzle 134 connects the passage 133 with the interior of bellows 127. The passage 10 thru nozzle 134 is of a very narrow cross-section, and restricts the flow of air between the exterior and interior of bellows 127.

As long as the aircraft is operated at a constant altitude, the pressures inside and outside the bellows 127 are equal. As the aircraft changes its altitude, as by climbing for example, the pressure outside the bellows decreases due to the increase in altitude. This change in pressure is not immediately communicated to the interior of bellows 127 because of the restriction in nozzle 134. Therefore, the bellows 127 tends to expand. The force acting to expand the bellows is proportional to the rate of change of the altitude of the aircraft, and the free end of the bellows 127 is positioned in accordance with the rate of change of the altitude of the aircraft.

There is mounted on the upper or free end of the bellows 127 a rod 135. The rod 135 extends thru a bushing 136 mounted in a transverse wall 141 of the housing 125. There is mounted on the upper end of rod 135 a movable switch contact 137, which cooperates with a pair of stationary contacts 138 and 140.

Above the wall 141, the interior of the casing 125 is hollow and is divided into two expandable chambers 145 and 146 by a flexible diaphragm 142. The diaphragm 142 carries at its center a bushing 143 thru which the rod 135 passes. A spring 144 is held in compression between an internal shoulder on the housing 125 and the diaphragm 142. The spring 144 biases the diaphragm 142 downwardly.

The chamber 145 under the diaphragm 142 is connected thru a passage 147 to the conduit 20 of Figure 1. The chamber 146 above the diaphragm 142 is connected thru a passage 148 to the conduit 25 of Figure 1. Therefore, as explained in connection with Figure 1, a pressure differential exists between chambers 145 and 146 which is proportional to the quantity of air entering the carburetor.

The rod 135 slides freely thru the bushing 143. A spacer 150 is fixed on the rod 135 just under the contact 137. The lower surface of spacer 150 cooperates with the upper surface of bushing 143. The spring 144 is chosen so that these surfaces are in engagement for all normal flight conditions encountered when the air entering the carburetor is greater than under idling conditions. Therefore, the contact 137 is positioned in accordance with the sum of two forces, one whose magnitude indicates the rate of change of altitude of the aircraft, and another whose magnitude indicates the quantity of air entering the engine, and hence the power produced by the engine. Both of these forces act upwardly when the conditions to which they respond change in a direction indicative of the need for a richer fuel and air mixture, and downwardly when the conditions indicate the need for a leaner fuel and air mixture.

Mounted on the top of the casing 125 are a pair of switches generally indicated at 151 and 152. The switch 151 includes a stationary contact 153 and a movable contact 154. The movable con-

5 tact 154 is attached to a leaf spring 155 which extends inwardly from the outer edge of casing 125. The inner end of leaf spring 155 carries a roller 156 having a surface of electrically insulating material. Stationary contact 153 is carried by another leaf spring 149 which extends substantially parallel to spring 155.

Similarly, the switch 152 includes a stationary contact 157 and a movable contact 158. The movable contact 158 is mounted on a leaf spring 160 which extends inwardly from the outer edge of the casing 155 opposite the switch 151 and carries at its inner end a roller 161, having a surface of electrically insulating material. Stationary contact 157 is carried by a leaf spring 159 which extends parallel to spring 160.

A mixture control shaft 162 is positioned above the rollers 156 and 161, and carries a mixture control lever 163 having a downwardly extending cam portion 164 adapted to engage the rollers 156 and 161, depending upon the angular position of the lever 163.

The leaf springs 155 and 160 are self-biased so that the contacts 154 and 158 tend to engage the stationary contacts 153 and 157, respectively. The mixture control lever 163 is shown in full lines in its lean position, wherein the contact 158 is separated from contact 157. When the mixture control lever 163 is in its rich position, shown in dotted lines in the drawings, the contact 30 154 is separated from contact 153.

Operation of Figure 2

When the mixture control lever 163 is in the 35 position shown in full lines in the drawings, the carburetor supplies the engine with a lean mixture. If the pilot then starts to climb without moving the mixture control lever to the rich position, the expansion of bellows 127 causes contact 137 to move upwardly into engagement with contact 138. This completes an energizing circuit for a signal 165 which is schematically illustrated as an illuminated signal bearing a suitable legend indicating that the mixture control lever 163 should be moved to its rich position. This energizing circuit may be traced from the upper terminal of a battery 166 thru a conductor 167, signal 165, a conductor 168, a multiple plug connector 170, a conductor 171, leaf spring 149, contact 153, contact 154, leaf spring 155, a conductor 172, contact 138, contact 137, rod 135, bushing 136, housing 125, a binding post 173, a conductor 174, connector 170, a conductor 175, and ground connections 176 and 177 to the lower terminal of battery 166. As soon as the pilot moves the lever 163 from the lean position to the rich position in accordance with the indication of the signal 165, the energization of signal 165 is discontinued by the separation of contacts 153 and 154. This separation takes place by virtue of the movement of cam 164 into engagement with roller 156.

It will be apparent that the same energizing circuit for signal 165 will be completed whenever the quantity of air entering the carburetor exceeds the value required to cause diaphragm 142 to lift rod 135 sufficiently to cause engagement of contacts 137 and 138.

When the mixture control lever 163 is in its dotted line, or rich position, a signal 180 is energized whenever the quantity of air flowing thru the carburetor falls below a predetermined value, and the rate of change of altitude of the aircraft falls below a predetermined value. The occurrence of these two conditions causes a downward movement of rod 135, thereby carrying con-

tact 137 into engagement with 149. This completes the energizing circuit for signal 139, which may be traced from the upper terminal of battery 166 thru conductor 167, signal 139, a conductor 181, connector 179, a conductor 182, leaf spring 159, contact 157, contact 158, leaf spring 160, a conductor 183, contact 148, contact 137, rod 135, bushing 136, casing 125, binding post 173, conductor 174, connector 170, conductor 175, and ground connections 176 and 177 to the lower terminal of battery 166. When the mixture control lever 163 is moved to its lean position in response to such a signal, the signal 139 is de-energized by the separation of contacts 157 and 158.

If preferred, audible or other sensible signals may be used in place of the illuminated signals illustrated.

While I have shown and described a preferred embodiment of my invention, other modifications thereof will occur to those skilled in the art, and I therefore intend my invention to be limited only by the appended claims.

I claim as my invention:

1. Signal apparatus, comprising in combination, a carburetor for an internal combustion engine on an aircraft, manually operable control means associated with said carburetor and movable between a first position wherein said carburetor supplies said engine with a rich fuel and air mixture and a second position wherein said carburetor supplies said engine with a lean fuel and air mixture, first double-throw switch means associated with said control means and moved to first and second circuit-closing positions when said control means is moved to its first and second positions, respectively, second double-throw switch means responsive to the altitude of said aircraft and moved to first and second circuit-closing positions when said aircraft reaches predetermined low and high altitudes, respectively, first electrical signal means for indicating that said manually operable control means should be moved to said second position, a first electrical circuit for energizing said first signal means and including said first and second switch means in series, said first circuit being closed when both said first and second switch means are in their first circuit-closing positions, second electrical signal means for indicating that said manually operable control means should be moved to said first position, and a second electrical circuit for energizing said second signal means and including said first and second switch means in series, said second circuit being closed when both said first and second switch means are in their second circuit-closing positions.

2. Signal apparatus, comprising in combination, a carburetor for an internal combustion engine on an aircraft, manually operable control means associated with said carburetor and movable between a first position wherein said carburetor supplies said engine with a rich fuel and air mixture and a second position wherein said carburetor supplies said engine with a lean fuel and air mixture, first double-throw switch means associated with said control means and moved to first and second circuit-closing positions when said control means is moved to its first and second positions, respectively, second double-throw switch means responsive to the altitude of said aircraft and moved to first and second circuit-closing positions when said aircraft reaches predetermined low and high altitudes, respectively, third double-throw switch means responsive to the attitude of said aircraft, said third switch

means being in a first circuit-closing position when said aircraft is level or diving and moved to a second circuit-closing position when said aircraft is climbing, first electrical signal means for indicating that said manually operable control means should be moved to said second position, a first electrical circuit for energizing said first signal means and including said first, second, and third switch means in series, said first circuit being closed when all of said first, second, and third switch means are in their first circuit-closing positions, second electrical signal means for indicating that said manually operable control means should be moved to said first position, and a second electrical circuit for energizing said second signal means and including said first switch means in series with said second and third switch means in parallel, said second circuit being closed when said first switch means and either said second or third switch means are in their second circuit-closing positions.

3. Signal apparatus, comprising in combination, a carburetor for an internal combustion engine on an aircraft, means in said carburetor for proportioning the quantity of fuel supplied to the engine in accordance with the quantity of air flowing thru said carburetor, altitude responsive means associated with said carburetor for compensating the action of said proportioning means, manually operable control means associated with said carburetor and movable between a first position wherein said carburetor supplies said engine with a rich fuel and air mixture and a second position wherein said carburetor supplies said engine with a lean fuel and air mixture, first double-throw switch means associated with said control means and moved to first and second circuit-closing positions when said control means is moved to its first and second positions, respectively, second double-throw switch means, means including said altitude responsive means for operating said second switch means to first and second circuit-closing positions when said aircraft reaches predetermined low and high altitudes, respectively, first electrical signal means for indicating that said manually operable control means should be moved to said second position, a first electrical circuit for energizing said first signal means and including said first and second switch means in series, said first circuit being closed when both said first and second switch means are in their first circuit-closing positions, second electrical signal means for indicating that said manually operable control means should be moved to said first position, and a second electrical circuit for energizing said second signal means and including said first and second switch means in series, said second circuit being closed when said first switch means and said second switch means are in their second circuit-closing positions.

4. Signal apparatus, comprising in combination, a carburetor for an internal combustion engine on an aircraft, means in said carburetor for proportioning the quantity of fuel supplied to the engine in accordance with the quantity of air flowing thru said carburetor, altitude responsive means associated with said carburetor for compensating the action of said proportioning means, a manually operable control member associated with said carburetor and movable between a first position wherein said carburetor supplies said engine with a rich fuel and air mixture and a second position wherein said carburetor supplies said engine with a lean fuel and air mixture, a

second member, means including said altitude responsive means for moving said second member between a first position corresponding to a predetermined low altitude and a second position corresponding to a predetermined high altitude, signal means operable to indicate the need for a change in position of said control member, and means responsive to the positions of said members to operate said signal means whenever both said members are in their respective first positions and whenever both members are in their respective second positions.

5. Signal apparatus for an aircraft, comprising in combination, signal means to indicate the need for a change in the ratio of fuel and air supplied to an internal combustion engine on said aircraft, and means responsive to the resultant of the altitude of said aircraft and the quantity of air flowing to said engine for operating said signal means.

6. Signal apparatus, comprising in combination, a carburetor for an internal combustion engine on an aircraft, manually operable control means associated with said carburetor and movable between a first position wherein said carburetor supplies said engine with a rich fuel and air mixture and a second position wherein said carburetor supplies said engine with a lean fuel and air mixture, first double-throw switch means associated with said control means and movable therewith to close first and second pairs of contacts when said control means is moved to its

first and second positions, respectively, a plurality of additional double-throw switch means, each of said additional switch means being responsive to one of a plurality of variable conditions affecting the temperature of said engine and movable to close a first pair of contacts when its associated condition assumes a value tending to decrease the temperature of said engine and to close a second pair of contacts when its associated condition assumes a value tending to increase the temperature of said engine, first electrical signal means for indicating that said manually operable control means should be moved to said second position, a first electrical circuit for energizing said first signal means and including all said first pairs of contacts in series, second electrical signal means for indicating that said manually operable control means should be moved to said first position, and a second electrical circuit for energizing said second signal means and including the second pair of contacts on said first switch means in series with all the second pairs of contacts of said additional switch means in parallel.

7. Signal apparatus, comprising in combination, signal means to indicate the need for a change in the ratio of fuel and air supplied to an internal combustion engine, and means responsive to the resultant of the rate of flow of combustion air to said engine and a condition affecting the temperature of said engine for operating said signal means.
